SOAKING PIT

John F. Mowat, La Grange, Ill., assignor to
United States Steel Company, a corporation
of New Jersey

Application June 1, 1948, Serial No. 30,256

5 Claims. (Cl. 263—20)

1

This invention relates to apparatus for heating ingots and, in particular, to a soaking pit having a separate combustion chamber and connections for conducting combustion gases from the chamber to the pit.

Although soaking pits have been improved in many respects in recent years, all modern pits known to me have burners firing directly thereto. Considerable difficulty is still experienced, therefore, as a result of flame impingement on the ingots. This causes "washing" or local overheating and melting of the ingots as well as excessive oxidation thereof, both of which impair the quality of the product. Fuel consumption remains high, furthermore, despite the general use of recuperators. It is accordingly the object of my invention to provide a soaking pit constructed to heat ingots solely by contact of hot combustion gases without direct flame impingement and to reduce the fuel consumption.

In a preferred embodiment and practice, I provide a combustion chamber adjacent the pit and effect substantially complete burning of the fuel therein. Combustion gases are led from the chamber and introduced into the pit through inlet ports spaced around the top thereof. After passing downwardly over the ingots, the gases are exhausted through outlet ports spaced around the bottom of the pit. This causes the pit to be filled with gas at substantially uniform temperature and pressure. The inlet and outlet ports communicate, respectively, with supply and exhaust flues extending around the pit. The combustion chamber is located at one side of the pit and is connected directly to the supply flue. Air for combustion is heated by recuperators in the stack flue connection. I also provide a heat-exchange wall for the combustion chamber and cause the entering air to pass through it to cool the wall and heat the air further.

A complete understanding of the invention may be obtained from the following detailed description and explanation which refer to the accompanying drawings illustrating a present preferred embodiment. In the drawings,

Figure 1 is a central longitudinal vertical section through the soaking pit of my invention and the associated combustion chamber;

Figures 2 through 4 are transverse sections to a reduced scale taken along the planes of lines II—II, III—III and IV—IV, respectively, of Figure 1;

Figure 5 is a horizontal section taken along the plane of line V—V of Figure 1; and

Figure 6 is a plan view of the pit with the cover removed.

2

Referring in detail to the drawings, the apparatus of my invention comprises a soaking pit 10 and a combustion chamber 11 extending across one side thereof. The drawings show only the walls of the chamber and pit, the structural binding thereof being omitted as well as dampers or other flow-control means. As shown in Figures 5 and 6, the pit is rectangular in plan, being defined by side walls 12, and is open at the top, being provided with a cover 13 removably disposed thereover. The usual sand seal 13a extends around the top of the pit. The walls of the pit and combustion chamber are constructed in the known manner by laying up brick of suitable composition and characteristics on a foundation 14, the pit, combustion chamber and hot-gas flues connected therewith, as will be described in detail later, being lined with refractory brick. The bottom of the pit, indicated at 15, comprises a refractory hearth laid on supporting beams 16 and provided with a layer of coke breeze in which the ingots to be heated are stood on end.

As shown in Figures 1 and 5, the combustion chamber 11 has a length and height somewhat greater than the corresponding dimensions of the pit 10. The length and height of the chamber 11, furthermore, are several times the width thereof. The chamber is divided by wall 17 into forth-and-return passes 18 and 19 connected by a port 20. The wall 17 is hollow and is provided with vertically spaced baffles 21 defining a continuous passage therethrough for a purpose which will appear shortly. The pass 18 is provided with a baffle 22 and the pass 19 with baffles 23 which cause turbulence in the combustion gases flowing therethrough and also brace and stay the walls of the combustion chamber.

Burners 24 fire into the pass 18 of the combustion chamber, being supplied with any desired type of fuel from a suitable source through a connection 25. This connection extends through an air chamber 26 which receives air preheated for combustion, through a downcomer duct 27 from a source which will be described later. The supply of fuel and air to the burners 24 is preferably controlled so that combustion of the fuel is substantially completed before the burning gases pass upwardly over the baffle 22. After passing the baffle, the gases flow downwardly, through port 20 and thence back through the return pass 19 around the baffles 23.

A flue 28 for supplying hot gases to the pit 10 extends about the latter at a level somewhat below the top, the flue being rounded at the corners, as indicated at 28a, to facilitate smooth flow of the gases therethrough. A port 29 extends from

the burner end of pass 19 to the flue 28 merging with the latter at one corner tangentially of the curve thereof, as shown in Figure 5. The walls 12 of the pit are recessed to provide a ledge or shoulder 30 spaced a short distance below the top. Offtake passages 31 branching from flue 28 extend upwardly therefrom and terminate in inlet ports 31^a opening upwardly from this ledge, as shown in Figure 1. The passages 31 are distributed substantially uniformly along the four sides of the pit, each side having a multiplicity of passages therein, as shown.

By virtue of the construction described, hot combustion gases flowing from chamber 11 through the passage 29 into the flue 28 pass upwardly through the passages 31, strike the bottom of the cover 13 and are thereby deflected downwardly into the pit. The flue 28 being continuous, any portion of the gases flowing therethrough which does not pass upwardly through the passages 31 is recirculated on returning to the intersection of the passage 29 with the flue where the recirculating gases mingle with the fresh combustion gases entering from the chamber 11. There will naturally be a slight fall in gas pressure from the passage 29 around the flue 28 in the direction of flow of gases. In order to insure substantially uniform flow of hot gases upwardly through passages 31 and downwardly over the rim of the pit at all points along the periphery thereof, I employ dampers in the form of refractory tiles 32. These dampers are adjusted manually to overlie the ports 31^a at the upper ends of the passages 31, to the extent necessary to maintain the desired uniform distribution of inflowing hot gases despite the fact that the pressure thereof diminishes gradually as they travel around the flue 28.

An exhaust flue 33 extends around the pit 10 at a level adjacent the bottom thereof and passages 34 extend thereto from outlet ports 34^a spaced along the side walls 12. The hot gases entering the top of the pit thus flow downwardly over the ingots standing therein, as indicated at 35, and thence outwardly through the passages 34 and flue 33. A stack flue 36 extends transversely of the pit below the bottom thereof and has an induced draft fan 37 therein on the burner side. A recuperator chamber 38 is formed between the flue 33 and the flue 36 and is provided with heat exchangers 39 in the form of banks of air tubes.

Air for combustion in the chamber 11 is supplied by a forced draft fan 40, the outlet of which is connected to a duct 41 terminating in a header 42 with which the tubes of one of the exchangers 39 communicate at one end. The several banks of tubes are connected in series by headers 43 and 42^a. The last bank is connected to header 43^a from which a duct 44 extends to the burner side of the chamber 11. As shown in Figure 3, this duct communicates with the lowermost of the several passes formed in the space within division wall 17 by the baffles 21. The air from the recuperator thus flows back and forth through the division wall absorbing additional heat therefrom. The air is thus, in effect, superheated and the wall is cooled simultaneously. Finally, the super-heated air flows out of the uppermost pass in the wall 17, through damper 21 and thence into the burners 24.

The operation of my improved soaking pit and the method of heating ingots which I am thereby enabled to carry out require no further explanation than has already been given in describing

the features of construction. It suffices to say that, as a result of introducing hot combustion gases into the pit substantially uniformly along the periphery of the rim and drawing them downwardly over the ingots, the latter are heated uniformly without direct impingement of any flame thereon. After coming in contact with surfaces of the ingots, the heating gases are withdrawn from the bottom of the furnace uniformly at all points along the sides.

It will be apparent that the invention is characterized by numerous advantages over prior soaking pits and ingot-heating practices. In the first place, local overheating and excessive oxidation of the ingots as a result of impingement of flame thereon are avoided. In the second place, since the combustion of fuel occurs in a confined space where conditions may be accurately controlled, greater economy in the consumption of fuel is achieved. This result is also aided by the high temperature to which the air for combustion may be heated by the combined action of the recuperators and super-heater. The ability to heat the various ingots substantially uniformly regardless of their exact location in the pit has already been mentioned.

The combustion of fuel in the chamber 11 is easily controllable, not only to assure the highest desirable temperature for efficient combustion but also a substantially neutral atmosphere of the combustion products in the pit, instead of one having oxidizing characteristics. A balanced draft may readily be maintained in the pit by a suitable control of the gases flowing outwardly through the exhaust duct 33. By this control, the pit is at all times maintained full of gas at uniform temperature and pressure, except when the cover is removed. At such times, fuel and air input to the pit should be reduced or discontinued. The stack draft may be controlled by a suitable damper or by varying the speed of the fan 37. Similarly, the fuel-air ratio may be controlled by a damper in the air-supply line or by controlling the speed of fan 40.

Although I have illustrated and described but a preferred embodiment and practice of the invention, it will be recognized that changes in the construction and procedure disclosed may be made without departing from the spirit of the invention or the scope of the appended claims.

I claim:

1. An ingot-heating furnace comprising a pit open at the top, having a bottom and side walls, a hot-gas supply flue formed in said side walls extending around the pit at a level adjacent the top of the side walls, inlet passages spaced around the pit branching from said flue and extending through the side walls adjacent the top thereof, an exhaust flue formed in said side walls extending around the pit at a level adjacent said bottom, outlet passages spaced around the pit and extending from the interior thereof to said exhaust flue, a combustion chamber adjacent said pit and a passage connecting said chamber to said hot-gas supply flue.

2. The apparatus defined by claim 1 characterized by said walls having a ledge adjacent the top thereof, said inlet passages terminating in ports opening upwardly through said ledge.

3. The apparatus defined by claim 1 characterized by said combustion chamber being constructed as an extension on one side of the pit and solid therewith, said chamber having therein a central partition defining forth and return

passes of a length and height at least equal to those of the pit.

4. An ingot-heating furnace comprising a pit open at the top, having a bottom and side walls, a combustion chamber constructed as an extension of the masonry mass of the furnace at one side thereof and solid therewith, said chamber having a central partition wall parallel to one of said side walls, defining forth and return passes of a length and height at least equal to those of the pit, a hot-gas supply flue extending around the pit and communicating therewith, and a passage connecting said return pass to said flue.

5. The apparatus defined by claim 4 characterized by said partition having air passages therein and said chamber having a burner, and means conducting air from said last-mentioned passages to said burner.
